CARL BREER, OF SUMMIT, NEW JERSEY, ASSIGNOR TO CHRYSLER CORPORATION, OF HIGHLAND PARK, MICHIGAN, A CORPORATION OF DELAWARE

METHOD OF FORMING EXPLOSIVE MIXTURES

Application filed January 26, 1923. Serial No. 615,129.

The construction forming the subject of this invention is particularly advantageous in connection with automobiles driven by internal combustion engines and provides a simple and efficient means for starting such engines particularly in cold weather. The common method of starting explosive engines in cold weather is to adjust the carburetor usually through the action of a choke valve so as to deliver many times over the proper quantity of liquid to form an explosive mixture. The result of this action is to supply a sufficient quantity of the lighter constituents of the fuel to form a sufficient amount of vapor to form with the incoming air an explosive mixture, the heavier constituents of the fuel being carried into the engine with all the attendant disadvantages incident to the delivery of liquid fuel to the engine. In carrying out the present invention the air is passed or drawn through the liquid fuel taking up a sufficient quantity of the lighter constituents of the fuel to form a rich mixture and this mixture is supplied to the engine initially to start the engine, after which the explosive mixture of the engine is formed in the usual manner by spraying the liquid into the incoming air as is done with the ordinary carburetor. The details of the structure forming the subject matter of the invention will appear more fully from the specification and claims.

The invention is illustrated in the accompanying drawings as follows:

Fig. 1 shows a side elevation in outline, parts being in section, of an automobile tank and connections leading to the intake tube.

Fig. 2 is an enlarged section of a device for introducing air through the fuel supply.

Fig. 3 a section on the line A—A in Fig. 2.

Fig. 4 a diagram showing a gasoline distillation curve.

1 marks the engine cylinder, 2 the intake tube or manifold, 3 a carburetor, 4 a throttle controlling the carburetor, 5 the carburetor nozzle, 5a the usual float chamber, 6 a vacuum tank, 7 a connection between the carburetor and the vacuum tank, 8 a connection between the intake manifold and the vacuum tank, and 9 a connection between the fuel

tank 10 and the vacuum tank. These are usually of ordinary construction. The tank is supplied with an opening 11 which is commonly provided with a re-enforcing ring 11a around its edges. A fitting 12 is secured to the ring 11a by screws 13. An air passage 14 extends through the fitting 12 and a protected cap 15 is carried by the fitting and extends over the upper end of the intake. A tube 16 extends downwardly from the opening 14 and is provided with a return bend 17 at its lower end from which a projecting tube 18 extends. The tube 18 enters an opening 19 in the fitting and the opening 19 discharges by way of an opening 20 to the top of the tank. The tube 18 is provided with a constriction 21 to which a nozzle 22 leads. For convenience the supply tank is vented by a small connection 16a leading from the upper end of the tube 16 to the upper end of the tube 18, thus putting the upper end of the tank through the opening 20 in communication at all times with the atmosphere through a vent opening fairly well protected.

A mixture outlet opening 23 is formed in the fitting 12 and this is connected by a pipe 24 with the intake manifold. It is supplied with a cut-off valve 25 which has a stem 26. This stem is supplied with an operating handle 27 and extends through the dash 28 of the automobile.

The opening 23 has an enlargement 29 in which is arranged a thimble 30 with a central opening 31. A disc 32 is arranged above the thimble 30 and it has the peripheral openings 33. The disc forms a check valve for preventing a back-flow of gases in the event of back-firing at the engine.

Under the broader features of my invention the return bend 17 might be omitted and the air drawn directly through the volume of the fuel but this may so expand the body of the fuel as to lift its level to a point where liquid gasoline would be drawn into the exhaust tube. Further there is a violent agitation and consequently a more intimate contact within the confined tube 18. In consequence there may be taken up some of the heavier constituents of the fuel as well as the lighter ends which vaporize at the tempera-

ture and pressure. By observing the distillation curve it will readily be seen that assuming that ten per cent of the fuel will vaporize at the pressure and temperature to which it is subjected one gallon in ten of the fuel can be perfectly vaporized at this temperature and forms an efficient explosive mixture. With the device a foglike mixture is formed just at the discharge side of the 5 constriction and consequently a mixture utilizing the lightest ends of the fuel may be taken up for starting purposes. With this device it will be noted that the engine is started by drawing off the lighter ends of the 10 fuel, the mixture being formed by passing air through the fuel much in excess of what the air takes up. In other words there is a sorting of the fuel for starting. After the starting is accomplished the continued action of 15 the engine is produced by spraying the fuel into the air with the ordinary carburetor 20 action.

With this form of starting the introduction 25 of liquid fuel into the engine in starting may be almost, if not entirely, obviated. I prefer to make the air vent approximately at the 30 center of the receptacle so that the tilting of the car will not affect an overflow of the air inlet.

30 What I claim as new is:—

1. The method of supplying explosive mixtures to internal combustion engines which consists in passing a stream of air in contact with a body of liquid fuel supplied by but 35 separated from a mass of fuel, taking the lighter ends of the fuel exposed to the air to form an explosive mixture, exclusive of other mixture, then during the continuation of the formation of such mixture augmenting it 40 with a mixture formed by spraying the residual liquid fuel into a stream of air, then stopping the flow of air through the liquid fuel, and continuing the formation of explosive mixture by spraying the fuel into the air.

45 2. The method of supplying explosive mixtures to internal combustion engines which consists in first passing a stream of air in contact with a body of liquid fuel used, taking up a portion of the fuel exposed to the 50 air to form an explosive mixture, while excluding other mixtures, then during the continuation of the formation of such mixture augmenting it with a mixture formed by spraying the residual liquid fuel into a stream 55 of air, then stopping the flow of air through the liquid fuel and continuing the formation of explosive mixture by spraying the residual fuel into the air.

60 3. The method of supplying explosive mixtures to internal combustion engines which consists in first passing a stream of air through a body of liquid fuel and taking up a portion thereof and preventing dilution of 65 said mixture by the exclusion of outer air after its passage through the liquid, then

during the continuation of such formation of such mixture augmenting it with a mixture formed by spraying the residual liquid fuel into a stream of air, then stopping the flow of air through the liquid fuel and continuing the formation of explosive mixture by spraying the fuel into the air.

70 In testimony whereof I have hereunto set my hand.
